CLAIM

The ornamental design for a hookah, as shown and described.

DESCRIPTION

FIG. 1 is top perspective view of a hookah, showing our new design.

FIG. 2 is a bottom perspective view thereof.

FIG. 3 is a left side elevational view thereof.

FIG. 4 is a right side elevational view thereof.

FIG. 5 is a front elevational view thereof.

FIG. 6 is a rear elevational view thereof.

FIG. 7 is a top plan view thereof; and,

FIG. 8 is a bottom plan view thereof.

The broken lines in the drawings depict portions of the hookah that form no part of the claimed design.
